MATCH BOX

Lycon Leroy Hudson, Tampa, Fla.

Application May 21, 1938, Serial No. 209,347

1 Claim. (Cl. 206—31)

My invention relates to improvements in match boxes and the primary object of the invention is to provide a simply constructed, inexpensive device of this character for containing the usual box of matches of commerce and providing for ready access to the matches and their quick and easy extraction from the box.

Another object is to provide a match box of the character and for the purpose above set forth, which is equipped with means for disposing of burnt matches in the form of drawer-like receptacle removable from the match box at will for the purpose of emptying.

Other and subordinate objects are also comprehended by my invention, all of which, together with the precise nature of my improvement will be readily understood from the succeeding description, when read in conjunction with the drawings accompanying and forming part of this specification.

In said drawings,

Figure 1 is a view in front elevation of a match box constructed in accordance with my invention.

Figure 2 is a view in side elevation.

Figure 3 is a view in vertical section taken on the line 3—3 of Figure 1 looking in the direction indicated by the arrows.

Figure 4 is a view in transverse section taken on the line 4—4 of Figure 1 also looking in the direction indicated by the arrows.

Figure 5 is a fragmentary view in vertical section taken on line 5—5 of Figure 2.

Figure 6 is a fragmentary view in transverse section taken on the line 6—6 of Figure 3 looking downwardly.

Figure 7 is a fragmentary view in vertical section taken on the line 7—7 of Figure 2.

Figure 8 is a similar view taken on the line 8—8 of Figure 2.

Figure 9 is a view in perspective of the burnt match container, and

Figure 10 is a view of the blank of which the match box is formed.

Referring to the drawings by numerals, the match box of my invention comprises an elongated substantially rectangular receptacle having a front wall 1, a rear wall 2, side walls 3, and a bottom wall 4 adjacent one end of the receptacle. The top of the receptacle is open. The side walls 3 extend at their upper ends slightly beyond the front wall 1 to provide side guides for facilitating the insertion of a box of matches into the receptacle. The guides are designated by the numerals 5. The rear wall 2 extends be-

yond both ends of the side walls 3 to provide attaching portions 6 by means of which the receptacle may be secured to a wall, door, or other fixed part, open end uppermost and by screws 7 passing through said portions 6.

Slightly above its transverse center, the front wall 1 is apertured as at 8 said aperture extending from side to side of the receptacle and having an arched upper edge 9. Extending through the aperture 8 and resting on the lower edge thereof, 10 is a partition member 10 dividing the receptacle into upper and lower compartments 11 and 12. The partition member 10 protrudes out of the aperture 8 and is formed into a tray 13 in front of said aperture having side walls 14 and a rounded bottom wall 15. The side walls 13 extend slightly into the aperture 8 and the sides of said aperture 8 are bounded by flanges 16 crimped around the rear ends of said side walls as best shown in Figure 6 whereby the tray 13 and partition member 10 are secured to the receptacle at the front thereof. The rear side of the partition member 10 has formed thereon a tongue 17 inserted through a slot 18 in the rear wall 2 and crimped against said wall whereby the partition 25 member is secured at the rear thereof to the receptacle. The aperture 8 extends well above the tray 13 so that access may be readily had by the fingers to the compartment 11.

The bottom wall 4 is cut out of one side wall 3 as best shown in Figure 10 and bent downwardly into proper position, said wall being provided with a tongue 19 inserted through a slot 20 in the opposite side wall and crimped against said wall. By cutting out the bottom wall 4 in the manner described a rectangular opening 21 is provided in the side wall from which said wall 4 is cut affording access to the compartment 12 at the bottom of the latter.

A drawer-like container 22 is slidably mounted 40 on the bottom wall 4 for removal through said opening 21. The container 22 has a front wall 23 adapted to close the opening 21. A ring-like finger grip member 24 is suitably affixed to the front wall 23 of the container 22 for manipulating the latter. Intermediate the partition member 10 and the top of the opening 21 the front wall 1 is provided with a transversely extending slot 25 formed by cutting out a flap 26 in said wall 1 and bending the latter outwardly and upwardly. The flap 26 forms a trough at the lower edge of the slot 25. As will be understood, the slot 25 and trough, designated 27, are for use in depositing matches into the container 22. The side walls 3 having the opening 21 therein is punched out- 55

wardly adjacent the upper end thereof to provide a match scratching panel 28 thereon.

The described receptacle is formed from a single blank of sheet tin shown in Figure 10. The blank comprises a portion 30 for forming the front wall 1 cut out, as at 31 to provide the aperture 8 and flanges 16 and also cut out as at 32 to provide the slot 25 and flap 26. Upon opposite sides of the portion 30 are portions 33 adapted to be bent along parallel lines 34 to form the side walls 3, one of the portions 33 being cut to provide the described aperture 21 and bottom wall 4 as previously described. The portion 33 has the panel 29 punched therein and has an adjoining portion 35 adapted to be bent thereon along the line 36 to form the back wall 2. One of the portions 33 has the aforementioned slot 20 cut therein and the portion 35 has the slot 18 also cut therein. The free edge of portion 35 and the appropriate portion 33 are adapted to be bent along the lines 37 and 38, respectively, and to be crimped together as best shown at 39 in Figure 4.

In the use of the described invention a box 25 of ordinary matches of commerce is inserted into the compartment 11 open at one end and open end downward with said end resting upon the partition member 16. In this position of the box of matches, the matches may be reached 30 through the aperture 8 as will be understood. The matches are taken from the tray 13 as will be understood. Burnt matches are deposited in the container 22 by way of the slot 25. When the container 22 is full it is removed in a manner 35 which will be apparent, and emptied.

As will now be seen, the match box of my invention may be easily and economically constructed. After a box of matches has been placed in the container the only necessary han-

dling of matches is when the same are withdrawn and lighted. Matches do not have to be taken from their original package and then placed in the match box as is the case with other match boxes of commerce. This box when once 5 fastened in position for use does not have to be removed for any reason. Full boxes of matches can be placed in the top of my match box and burnt matches easily disposed of by removing the container 22 at any time. 10

The foregoing will, it is believed, suffice to impart a clear understanding of my invention without further explanation.

Manifestly, my invention as described is susceptible of modification without departing from 15 the inventive concept and right is herein reserved to such modifications as fall within the scope of the subjoined claim.

What I claim is:

A match box for attachment to a wall or the like comprising an elongated rectangular receptacle having an open upper end, a closed lower end and a front wall apertured intermediate said ends of the receptacle, the aperture extending across said front wall, and a transverse partition member in the receptacle at the bottom of said aperture forming in the receptacle an upper compartment adapted to contain a box of matches resting on said partition and accessible through said aperture, said partition having a tray-like 25 extension protruding through the bottom of said aperture in front thereof, said extension having side walls, said side walls at the rear edges thereof and the front wall of the box being crimped into interlocking relation to secure the tray in 30 35 position, and said aperture arching above said side walls to facilitate insertion of the fingers therethrough over said walls.

LYCON LEROY HUDSON.
